UNITED STATES PATENT OFFICE.

WILLIAM H. CRICHTON-CLARKE, OF NEW YORK, N. Y., ASSIGNOR TO GILLETTE
SAFETY RAZOR COMPANY, OF BOSTON, MASSACHUSETTS, A CORPORATION
OF MASSACHUSETTS.

BLADE-SHARPENING MECHANISM.

1,106,548.

Specification of Letters Patent. Patented Aug. 11, 1914.

Application filed May 16, 1907. Serial No. 374,075.

To all whom it may concern:

Be it known that I, WILLIAM H. CRICHTON-CLARKE, a citizen of the United States, residing in the city of New York, borough 5 of Manhattan, county and State of New York, have invented certain new and useful Improvements in Blade-Sharpener Mechanism, of which the following is a full, clear, and exact specification.

- 10 My invention relates to blade sharpening mechanism and the object of my invention is to produce a machine that will simultaneously operate on opposite edges of a double-edged blade, and that will be adapted for 15 individual use and in connection with an ordinary razor strop, and to that end my invention consists in the employment of a suitable holding device for holding the blade and means for rocking the same, so that the 20 opposite edges thereof shall simultaneously engage properly disposed abrading surfaces, such as a strop.

Figure 1 is an end elevation of one practicable form of my device in position upon 25 a strop. Fig. 2 is a side elevation of said device with a blade in position, partly broken away. Fig. 3 is a cross-section on the line 3—3 of Fig. 1. Fig. 4 is an enlarged end view of the rocking member and associated parts, partly in section. Figs. 5 and 6 are details of the blade support. Fig. 7 is a cross-section on the line 7—7 of Fig. 1. Fig. 8 is a detail of the returning spring for the 30 rocking member.

35 Upon a frame plate 1 is mounted a pair of strop-guiding rollers 2, 3, which are situated opposite each other upon said plate and receive the strop A on their inner faces and guide it over a third roller 4, around which 40 it passes, returning on itself in substantially parallel paths, thereby forming two substantially parallel stropping surfaces, B, C, separated from each other a distance equal to the diameter of roller 4.

45 Within the space between the normal positions of the said two stropping surfaces when the strop is in position with a portion bent itself, is located a blade-holder. The blade-holder is shown mounted on a rod 5 carried by the frame plate 1. A sleeve 7 is mounted on the rod 5 for rotation. Longitudinal movement of the sleeve is prevented by an enlarged head 6 forming an annular flange or shoulder carried by the

rod 5, at its outer or free end. The blade-holder is shown carried by this sleeve and comprises a base plate 8 preferably flat to conform to the shape of the blade and secured to or forming part of the sleeve, and a swinging clamping arm 9 hinged to the 60 plate 8 preferably at its inner end. The arm 9 is shown provided with a perforation at 10 at its outer end to receive a post 11 carried by the plate 8 and a retaining arm 12 which is hinged to said post to swing over 65 the clamping arm when it is in its closed position for the purpose of locking the clamp in its closed or clamping position.

The blade to be sharpened, indicated by 13, is held from edgewise movement upon 70 the base plate by some suitable means. Lugs 14 are shown carried by the plate 8 and located in position to pass through suitable perforations in the blade and in the arm 9.

As the device is moved relatively to the 75 strop as a whole the blade-holder will be rocked from side to side. The rocking means for the blade-holder is shown comprising a pinion 16 fast with the inner end 15 of the oscillatory sleeve 7. The pinion 16 is shown spaced from the face of the plate 1 by a washer 17 carried by the rod 5 between such pinion and frame. This pinion 80 is in mesh with a sector rack 18 forming part of a rocking member 19. The rocking 85 member 19 is shown mounted on a stub shaft 20 carried by the frame plate 1. The rocking member is spaced from the face of the frame plate by a washer 21, carried by the 90 stub shaft. The rocking member is shown with a pair of flaring arms forming a space between them within which is the sector 95 rack 18 and the pinion 16. These arms are united at their outer ends by a sector having the stub shaft 20 as a center. The face of the sector 22 is in position to be engaged by the strop face B. The sector will be moved by the strop as the same moves relatively to the stropping machine, thereby, through the rack 18 oscillating the pinion 16 and causing 100 the opposite edges of the blade 13 to bear upon the strop. For instance, if the strop is moving in the direction of the arrow (Fig. 1), the rocking member 19 will cause the blade to be rocked so that edge 13^a of the 105 blade will contact with part B of the strop, and 13^b will contact with part C, and upon a reversal of the relative movement of the

strop and stropping machine, the contacting edges will alternate and 13^a will engage C and 13^b will engage B.

For the purpose of facilitating the freeing of the blade from the strop and preventing the cutting of the strop upon reversal of strop movement I provide elastically yieldable means against which the blade is held in contact with the strop, and this may be in the form of spring 23 coiled around a post 24 secured to the frame so as to be out of the path of the strop, and having its two ends, projecting upwardly and passing on each side of a pin 25 in the lower part of the rocking member 19 and a retaining pin 26 in the frame. Upon a movement of the rocking member, pin 25 will engage and carry with it one arm of the spring, and the opposite arm will remain in contact with fixed pin 26 and will thereby flex the spring.

To facilitate the quick release of the razor blade from the strop, I provide the strop near its ends with slots D, which are in the path of the sector 22. Upon arriving at said slots, the sector will immediately be released from the strop and spring 23 will then cause the blade to resume its normal idle position.

It is obvious that numerous modifications may be made in my invention without departing from the spirit thereof, and I do not mean to limit myself to the specific form shown, but

What I claim and desire to secure by Letters Patent is:

35 1. A razor stropping machine for stropping a double-edged blade, comprising means for supporting oppositely disposed abrading surfaces, a blade holder and means for causing both edges of said blade to simultaneously engage said abrading surfaces, and means for returning said blade holder to normal position, substantially as described.

45 2. A razor stropping machine for stropping a double-edged blade, comprising a frame having guides located in position to bend a portion of the strop upon itself to present a pair of parallel oppositely disposed abrading surfaces, a holder for a double-edged blade carried by the frame between the position of the pair of parallel surfaces and means actuated by the strop upon the relative movement of said machine and said strop for causing both edges of a 55 blade in said holder to simultaneously engage said abrading surfaces, substantially as described.

50 3. A razor stropping machine for stropping a double-edged blade, comprising a rocking blade support, adapted to expose both edges of the blade, means for supporting abrading surfaces on opposite sides of said support, in position to be engaged by both sides of both edges of said blade, and 55 means for rocking said support actuated by

the relative movement of the machine and the abrading surfaces, substantially as described.

4. A razor stropping machine for stropping a double-edged blade, comprising a 70 rocking blade support, adapted to expose both edges of the blade, means for supporting abrading surfaces on opposite sides of said support, in position to be engaged by both sides of both edges of said blade, and 75 means for rocking said support actuated by the relative movement of the machine and the abrading surfaces, and means for returning said blade support to normal position, substantially as described.

5. A razor stropping machine for stropping a double-edged blade, comprising a rocking blade support, adapted to expose both edges of the blade, means for supporting abrading surfaces in position to be engaged 85 by both sides of both edges of said blade so disposed that a relative movement of said machine and said abrading surfaces will cause the same to travel in opposite directions on the opposite sides of said blade support, and means actuated by such relative movement for rocking said blade support, 90 substantially as described.

6. A razor stropping machine for stropping double-edged blades, comprising a 95 frame, strop guides, rollers mounted thereon, a rocking blade support mounted in said frame intermediate said guides, a rocking member mounted in such frame in the path of the strop, a connection between said rocking member and said blade support whereby, as the rocking member is moved the blade support is rocked, causing the opposite edges of the blade to simultaneously engage said strop, substantially as described.

100 7. A blade support for a double-edged razor blade, comprising a fixed bearing, a sleeve rotatably mounted thereon, means on said sleeve for attaching a blade thereto and located in position to expose both edges of the blade, and a clamping member pivoted to said sleeve, substantially as described.

110 8. A stropping machine for double-edged razor blades, comprising a frame, a rocking blade support in said frame, strop guides in 115 said frame so disposed as to cause said strop to move in opposite directions on the opposite sides of the blade support, a rocking member engaging said strop, and a connection between said rocking member and said strop whereby, upon relative movement between said machine and said strop, the blade is rocked to cause its opposite edges to simultaneously engage said strop at opposite sides upon movement in one direction, and 120 upon the other sides on a reverse of said movement, substantially as described.

125 9. A stropping machine for double-edged razor blades, comprising a frame, a handle, strop-guiding rollers at opposite ends of 130

- 5 said frame, a blade-supporting spindle intermediate said rollers, a sleeve rotatably mounted therein, a blade clamp on said sleeve, a pinion likewise on said sleeve, a 10 rocking member journaled in said frame, a rocking surface therein in the path of the strop, and a rack on said rocking member engaging said pinion, substantially as described.
- 10 10. A stropping machine for double-edged razor blades, comprising a frame, a handle, strop-guiding rollers at opposite ends of said frame, a blade supporting spindle intermediate said rollers, a sleeve 15 rotatably mounted thereon, a blade clamp on said sleeve, a pinion likewise on said sleeve, a rocking member journaled in said frame, a rocking surface therein in the path of the strop, a rack on said rocking member 20 engaging said pinion, and a spring for automatically returning said rocking member to upright position, substantially as described.
11. A stropping machine for double-edged razor blades, comprising a strop, a frame, a handle, strop-guiding rollers at opposite ends of said frame, a blade-supporting spindle intermediate said rollers, a sleeve 25 rotatably mounted thereon, a blade clamp on said sleeve, a pinion likewise on said sleeve, a rocking member journaled in said frame, a rocking surface therein in the path of the strop, a recess at the end of said strop for receiving said rocking surface, and a 30 rack on said rocking member engaging said pinion, substantially as described.
12. A stropping machine for double-edged razor blades, comprising a frame, strop-guiding rollers so disposed therein 35 that the strop will be caused to traverse said frame in parallel paths and in opposite
- 45 directions, a blade support mounted in said frame between said strop paths to rock, means on said support for securing a blade thereto so as to expose both its edges, a rocking member mounted in said frame in position to engage said strop, and a connection between said rocking member and said blade support, substantially as described.
13. A stropping machine for double-edged razor blades, comprising a frame, strop-guiding rollers so disposed therein that the strop will be caused to traverse said frame in parallel paths and in opposite directions, a blade support mounted in said 50 frame between said strop paths to rock, means on said support for securing a blade thereto so as to expose both its edges, a rocking member mounted in said frame in position to engage said strop, a spring engaging 55 said rocking member for retracting same, and a connection between said rocking member and said blade support, substantially as described.
14. The combination with a frame, of a 60 blade holder having means for positioning a double edged blade for exposing both edges thereof mounted on the frame, strop guides on the frame located in position to guide a strop past the opposite sides of the 65 holder, a strop disposed on the guides, and holder actuating means for causing the respective edges of the blade held thereby to alternately engage the strop at the respective sides of the holder.
- 75 In testimony whereof, I have hereunto set my name in the presence of two subscribing witnesses.
